CLAIM

The ornamental design for the bottle, as shown and described.

DESCRIPTION

FIG. 1 is a front perspective view from above and right side of the bottle;

FIG. 2 is a front elevational view thereof;

FIG. 3 is a rear elevational view thereof;

FIG. 4 is a left side view thereof;

FIG. 5 is a right side view thereof; and,

FIG. 6 is a plan view thereof.

The broken line showing is for illustrative purposes only, and

forms no part of the claimed design.
